[57] CLAIM

The ornamental design for a storage container with doors at one end, as shown and described.

DESCRIPTION

FIG. 1 is a perspective view of the top, front and left side views of a storage container with the doors open and embodying the invention;

FIG. 2 is a fragmented right side elevational view thereof, wherein the doors are closed;

FIG. 3 is a fragmented top plan view thereof;

FIG. 4 is a fragmented bottom plan view thereof;

FIG. 5 is a fragmented left side elevational view thereof;

FIG. 6 is a right end view thereof; and,

FIG. 7 is a left end view thereof.
